AIR STERILIZING AND CONDITIONING APPARATUS

David E. Wehner, Allison Park, Pa.

Application July 15, 1935, Serial No. 31,534

2 Claims. (Cl. 257—9)

This invention relates to apparatus for conditioning the air of dwellings, halls, churches, theatres, railway cars, ships, and other places whereby to render the air pure and free of disease bacteria and harmful sediments.

A further object is to provide apparatus of this type which combines in a single organization, filters, humidifying devices, a heater for controlling the temperature from 180° F. to 400° F. to destroy bacteria, and a cooling unit forming the last stage for tempering the air just prior to its supply to the dwelling, structure or carrier to which the apparatus is associated.

A further object is to provide apparatus of this type which is compact, capable of being economically operated, automatically controlled, and formed of a few strong, simple and durable parts which are easy to manufacture and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a longitudinal sectional view of an apparatus constructed in accordance with the invention.

Figure 2 is a detail cross sectional view taken on the line 2—2 of Figure 1.

Figure 3 is a detail longitudinal sectional view showing the humidifier parts on a larger scale than in Figure 1.

Figure 4 is a longitudinal sectional view similar to Figure 3 but showing the humidifying wicks choked.

Figure 5 is a cross sectional view taken on the line 5—5 of Figure 3.

Figure 6 is a detail cross sectional view through the solenoid for controlling the grids of the humidifying unit.

Referring now to the drawings in which like characters of reference designate similar parts in the various views, 10 designates a casing which may be formed in one piece or may be formed in 50 sections to enclose the coordinate parts for filtering, humidifying, sterilizing and cooling the air. The casing is provided with a flared intake end 11.

A pair of filters 12 and 13 are mounted in the casing and each preferably consists of spaced 55 foraminous frames 14 formed of wire mesh or

other suitable material, between which is confined a filtering element 15 formed of cotton gauze or other suitable material. A conventional electric fan 16 is mounted in the casing between the filters to draw air into the casing through 5 the filter 12 and force the air through the filter 13 to remove dust particles and other foreign matter from the air. The lead wires 17 and 18 of the fan motor are connected to the line supply wires 19 and 20 which supply current to the 10 various electrically operated components of the apparatus.

An electric fan 21 is mounted in the casing beyond the filter 13 and the lead wires 22 and 23 are connected to the line wires 19 and 20. The 15 fan 21 forces the filtered air through a humidifying unit comprising a plurality of wicks 24 which are arranged in vertical rows transversely of the casing, the wicks of each row being staggered relatively to the wicks of the next adjacent 20 row, as best shown in Figure 5.

The wicks of the humidifying unit are suitably secured at the upper ends to the casing preferably being attached to pins 25 depending from the top of the casing, by means of tie wires or cords 26, as best shown in Figure 3. The lower ends of the wicks extend into a water tank 27 which is provided at the top with a flange 28 which is bolted to the bottom of the casing, as shown at 29. The wicks absorb water from the tank by 30 capillary attraction as will be understood and the forced draft from the fan 21 carries the moisture from the wicks to humidify the air.

For controlling the humidity within predetermined limits a stationary grid 30 is fixed to one 35 side wall of the tank and is provided with spaced parallel fingers 31 which extend to the opposite side wall of the tank, as shown in Figure 5. A slideable grid 32 is mounted in the plane of the stationary grid by means of guide lugs 33 which 40 are carried by the grid and are slidably fitted in openings 34 formed in the opposite end walls of the tank. The movable grid is provided with spaced parallel fingers 35 which interdigitate with the fingers 31 of the stationary grid in such 45 manner that each row of wicks is confined between a fixed finger 31 and a movable finger 35. As a result when the movable grid is moved forwardly the wicks will be pinched or choked above the water level in the tank, as best shown in Figure 4, to prevent lifting of water from the tanks through the wicks. When the movable grid is withdrawn to normal position, as best shown in Figure 3, lifting of water through the wicks from 50 the tank is again permitted.

For controlling the grids 30 and 32 a moisture responsive switch 36 of conventional type is electrically connected to the line wires 19 and 20 and to a solenoid 37 by means of conductive wires 38 and 39. The solenoid is mounted on the bottom of the casing and the magnetic plunger 40 is connected by a non-magnetic stem 41 to the movable grid. When the switch 36 is closed by excessive humidity the solenoid is energized to move the movable grid and pinch the wicks 24 against the stationary grid to prevent water being lifted from the tank by the wicks. When the humidity falls to a predetermined lower limit the switch opens and de-energizes the electric magnet and permits the normal elasticity of the wicks to return the movable grid to open position and permit further lifting of the water from the tank by the wicks.

Referring again to Figure 1 it will be seen that the sterilizing unit consists of a plurality of resistance coils 42 which are suitably supported within the casing 10, the lower ends of all of the coils being connected together in series and being connected to the line wire 20 by a conductor wire 44. The upper ends of the resistance coils are connected by respective conductor wires 46 to stationary switch contacts 47 which may be arranged on a panel 48 secured to the casing. A movable switch contact 49 is connected by a conductor wire 50 to the line wire 19 and is moved upwardly into engagement with the contacts 47 in sequence to simultaneously energize as many of the resistance coils as may be required to impart a predetermined temperature to the air sufficient to destroy bacteria, which temperature should be within the range of 180° F. to 400° F.

A thermostat 51 of any preferred type is located in the casing in the path of the air emerging from the sterilizing unit and the plunger 52 of the thermostat is connected by a link 53 to a rod 54 which carries the movable switch contact 49 and which is slidably mounted on a guide 55 on the panel 48. A counterbalancing weight 56 is provided with a cable 57 which is trained over pulleys 58 on the panel and connected with the rod 54 to counterbalance the weight of the rod and switch contacts and permit the thermostat to easily operate the switch contact 49. The thermostat through the connections just described automatically cuts in or cuts out as many of the resistance coils as may be necessary to maintain the specified range of temperatures in the air stream emerging from the sterilizing unit.

The cooling unit forms the last stage and tempers the air just prior to its supply to the dwelling, structure or carrier with which the apparatus is associated. The unit comprises upper and lower headers 59 and 60 which are connected by vertical pipes 61, the pipes preferably being arranged within the casing 10 and the headers outside of the casing. The headers and pipes are filled with brine or other suitable cooling medium which is caused to circulate by a pump 62 the outlet of which is connected to the lower header and the inlet of which is connected to a pipe 63 which enters the lower header 64 of a refrigerating chamber 65. The upper header 66 of the chamber is connected to the upper header of the cooling unit by a pipe 67. The upper and lower headers of the refrigerating chamber are connected by vertical pipes 68 through which the brine is circulated by the pump. In the spaces around the pipes 68 a refrigerant is circulated by a motor driven refrigerating unit 69 of the conventional

compressor type, which is connected to the upper and lower ends of the chamber by pipes 70 and 71.

The brine is automatically maintained at a predetermined temperature by means of a heat responsive switch 72 which is disposed within the outlet 73 of the casing 10. The switch is preferably of the mercury type moving a stem 74 which carries a switch contact 75 into or out of engagement with a fixed switch contact 76. A conductor wire 77 connects the fixed switch contact with the main line wire 20. A conductor 78 connects the movable switch contact 75 with one of the motor terminals 79 of the refrigerating unit. A conductor wire 80 connects the other terminal of the refrigerating unit motor to one terminal of a motor 81 which drives the pump 62 by means of a belt drive 82. The other terminal of the motor 81 is connected to the line wire 19 by a conductor wire 83.

When the temperature of the conditioned air in the outlet 73 rises beyond a predetermined degree the switch 72 moves the switch contact 75 into engagement with the switch contact 76 and closes the circuit through the refrigerating unit motor and through the pump operating motor. Then the brine is circulated through the pipes 61 and 68 of the cooling unit and refrigerating chamber while simultaneously the refrigerant in the refrigerating chamber is compressed from gaseous to liquid form in the usual manner and delivered to the spaces between the pipes 68 to lower the temperature of the brine. When the predetermined temperature is restored in the outlet 73 the circuit is opened by disengagement of the switch contact 75 from the switch contact 76 to de-energize both motors.

In operation, air is drawn into the casing 10 through the filter 12 by the fan 16 and forced through the filter 13 by the combined action of the fan 16 and the fan 21. The filtered air is then forced by the fan 21 against the damp wicks 24, and through the spaces between the wicks, and moisture is taken up to humidify the air. The humidified air is blown against the coils 42, and through the spaces between the coils, where high temperatures are encountered sufficient to destroy all bacteria. The bacteria free air then impinges against the cooling pipes 61 and during passage through the spaces between the pipes the temperature is lowered to a predetermined degree which will be comfortable to the occupants of the dwelling, structure, or carrier with which the apparatus is associated.

The motors of the fans 16 and 21 are controlled by a rheostat 84 to supply air in any predetermined volume to suit conditions to be encountered. The humidifying, sterilizing and cooling units are automatically controlled by their respective moisture and temperature responsive switches so that the apparatus automatically maintains predetermined temperature and humidity in the air freed from bacteria and harmful sediments.

For automatically supplying the tank with water, a water supply pipe 85 enters the tank 65 and is provided with a valve 86 which is controlled by a float 87.

From the above description it is thought that the construction and operation of the invention will be fully understood without further explanation.

What is claimed is:

1. In air conditioning apparatus, the combination of a casing having inlet and outlet openings, means for creating a forced draft from the inlet 75

to the outlet opening; filters in the casing near the inlet opening, a water tank associated with the casing, wicks extending through the casing from the water tank in the path of said forced draft for humidifying the air, moisture responsive means for controlling the capacity of the wicks to lift water from the tank, a heater for heating the humidified air to a predetermined temperature sufficient to destroy bacteria, and means for cooling the humidified bacteria free air.

10 2. In air conditioning apparatus, the combination of a casing having inlet and outlet openings,

electric fans for creating a forced draft from the inlet to the outlet opening, filters near the inlet opening in the path of the forced draft, a water tank associated with the casing beyond the filters, wicks in the casing in said forced draft and projecting into the water tank, interdigitating grids for choking the humidifying wicks to prevent lifting of water from the tank, a moisture responsive switch for controlling the grids, a heater for heating the air to a temperature sufficient to 10 destroy bacteria, and a cooling unit for tempering the humidified bacteria free air.
